UNITED STATES PATENT OFFICE.

THOMAS H. SYMINGTON, OF BALTIMORE, MARYLAND, ASSIGNOR TO
THE T. H. SYMINGTON CO. OF BALTIMORE CITY, A CORPORATION
OF MARYLAND.

COVER FOR JOURNAL-BOXES.

No. 815,230.

Specification of Letters Patent. Patented March 13, 1906.

Application filed June 20, 1905. Serial No. 266,162.

To all whom it may concern:

Be it known that I, THOMAS H. SYMINGTON, a citizen of the United States, residing at Baltimore, in the State of Maryland, have 5 invented certain new and useful Improvements in Covers for Journal-Boxes, of which the following is a specification.

This invention relates to improvements in covers for journal-boxes, and has for its object 10 to provide an improved form of hinged lid which when closed will contact with and seat all the way around the face of the box-opening, and thus leave no space or opening whatever for the admission of dust and dirt to the 15 interior of the box.

The invention is illustrated in the accompanying drawings, in which—

Figure 1 illustrates a front view of the cover and also shows a portion of the hinge-joint on the box, and Fig. 2 illustrates a sectional elevation of the cover and a portion of the box.

Referring to the drawings by numerals, 1 designates the outer end of the journal-box, 25 which is provided with a faced-off surface or seat 2, which extends entirely around the box at the outer end and against which the lid seats. At the upper edge and in the center of the box is provided with a tubular hinge 30 member 3, which is stationary and which is provided with a flat surface 4 for a purpose to be presently described.

The lid 5, as shown in Fig. 2, has an outward arch in the vertical direction and is provided at the upper edge with tubular hinge-eyes 6, which project on opposite sides of the tubular member 3 on the box, and said hinge-eyes are provided on opposite edges with ribs 7. A pin 8 passes through the tubular hinge 40 3 and eye members 6 to hold the lid in place on the box. On the outer face and adjacent the upper edge the lid is provided with a rib 9, which is provided with a slot 10, and this slotted rib has position directly beneath the flat face 4. Below the rib 9 the lid has another rib 11, which is also provided with a slot 12, and below said slot a centrally-located horizontal groove 13 is also provided in the lid. It will thus be seen that the slots 10 and 45 12 and the groove 13, all of which are in the lid, have position in a central line extending downward below the flat face 4 on the hinge

member 3 of the box. The lid is imperforate or without opening, and its inner surface is an arched concave in the vertical direction and 55 is provided adjacent its four edges with a flat face 14, which extends uniformly around the said four edges and makes close contact with the faced-off surface or seat 2 around the four edges of the box-opening. The two side 60 edges of this are flush with the outer edges of the box-opening. On its outer surface the lid is provided with a projecting edge flange directly over the said flat face 14 at the inner surface. This outer edge flange is continuous 65 around the four edges and corners of the lid and serves to prevent the lid from being bent or distorted at said edges. A flat spring 15 has a hook 16 formed on its lower end, which turns inwardly and projects into the groove 70 13, formed in the lid, and said spring extends upwardly from said groove and passes through the slot 12 in the lower rib 11 and also through the slot 10 in the upper rib 9, and the upper end of said spring presses against the flat face 4 on the hinge member 3 of the box. It is obvious that by means of this spring 15 the inner flat rim-face 14 of the cover will be pressed firmly against the faced-off surface or seat 2 around the box-opening and thus maintain a tight 75 joint and exclude the dust and dirt.

The eye members 6 of the hinge, which are integral with the lid, have an improved construction consisting of a central cylindric part in which the metal is light or thin, and 85 this part is provided with two sides ribs or flanges 7, which are also relatively thin. This construction of eye member obviates the liability to distortion of the position of the eye member in casting the lid, and in case distortion has occurred this construction enables the same to be easily remedied by blows from a hammer, which will dent or bend the parts of the eye member, and thereby slightly shift its position relative to the lid and enable 90 the lid to be fitted on the box so that the lid-face 14 will accurately contact with the seat 2 around the box-opening. An inclined depression 18 is also provided on the outer surface of the lid below the groove 13, the deepest part of said incline being coincident with the bottom of said groove, which enables an edged tool to be inserted in the groove beneath the hook 16 on the spring, whereby the 100

latter may be raised and held out of the groove while driving the spring downward to remove it from the lid.

Having thus described my invention, what I claim as new, and desire to secure by Letters Patent, is—

A journal-box for railway-cars having a hinged lid which is provided on its outer surface with horizontal ribs having slots, a groove, 13, formed in the lid and an inclined depression, 18, also formed in the lid adjacent said groove—the deepest part of said depression leading into said groove and being coincident with the bottom thereof; and a flat

spring extending through said slots and having at one end a hook which projects into said groove, whereby when it is desired to remove the spring from the lid an edged tool may be moved along the inclined depression and forced into the groove beneath the said hook on the spring.

In testimony whereof I affix my signature in presence of two witnesses.

THOMAS H. SYMINGTON.
